(57) **CLAIM**

The ornamental design for a heat dissipating unit, as shown and described.

DESCRIPTION

FIG. 1 is a perspective view of a heat dissipating unit showing my new design;

FIG. 2 is a front elevational view thereof;

FIG. 3 is a rear elevational view thereof;

FIG. 4 is a left-side, elevational view thereof;

FIG. 5 is a right-side, elevational view thereof;

FIG. 6 is a top plan view thereof; and,

FIG. 7 is a bottom plan view thereof.

The broken line showing of portion of the heat dissipating unit is for illustrative purpose only and forms no part of the claimed design.
